Charles Croley

United States Patent Office.

CHARLES CROLEY, OF DAYTON, OHIO.

Letters Patent No. 63,616, dated April 9, 1867.

IMPROVED WINDOW FRAME.

The Schedule referred to in these Letters Patent and making part of the same.

TO ALL WHOM IT MAY CONCERN:

Be it known that I, CHARLES CROLEY, of Dayton, in the county of Montgomery, in the State of Ohio, have invented a new and improved Window Frame; and I do hereby declare that the following is a full and exact description thereof, reference being had to the accompanying drawing, and to the letters of reference marked thereon.

The nature of my invention consists in constructing a box-window frame, with a pocket-piece so constructed and attached that the sash may be readily removed, and the usual strips dispensed with.

To enable others skilled in the art to make and use my invention, I will proceed to describe its construction and operation.

The figure represents a perspective view of the window frame, with a portion of one side cut away to show the pocket-piece.

A represents the frame, containing the upper sash B and the lower sash C, which are held within grooves of the frame in the usual manner. These grooves may be formed within the frame proper, or by the usual strips, or by facings. A boxing is formed by cutting away the side of the frame, as represented, or by cutting through the side of the frame or otherwise. This boxing is made longer than the lower sash, and of the width of the sash and the parting strip, and beneath this boxing is a mortise in the sill of the frame. Into this boxing is fitted the pocket-piece D, to the upper end of which is a pin to stay the upper end in position within the boxing, the lower end fitting within a mortise in the sill F, by which it is held with the aid of a catch, e, the eccentric-like end of which rests against the side of the mortise. This catch has a shaft passing through the pocket-piece and a terminal plate, by which it is turned. The part of the pocket-piece D which corresponds to the parting strip used between the sashes is rounded near the bottom, and shortened to let the pocket-piece fall below its proper position.

The use will be readily comprehended by describing the operation of removing the sash. The catch e being turned about a quarter movement, the lower sash being first raised up, the pocket-piece descends sufficiently to release the pin at the top, then bringing the lower sash down, it is pressed towards the side, which disengages the opposite side from the groove; it is then lifted out; then the upper sash is brought down and removed in a similar manner. Thus the sash is removed without the necessity of removing the strips, and also obviating the use of strips.

What I claim as my invention, and desire to secure by Letters Patent, is—

The pocket-piece D, having the catch e, or its equivalent, and its arrangement with reference to the window frame A and sash B and C, in the manner substantially as and for the purpose described.

CHARLES CROLEY.
